(57) **CLAIM**

The ornamental design for a card with blended magnetic stripe, as shown and described.

DESCRIPTION

FIG. 1 is an isometric view of the card with blended magnetic stripe showing our new design; FIG. 2 is a bottom view thereof;

FIG. 3 is a top view thereof;

FIG. 4 is a first end view thereof;

FIG. 5 is a second end view thereof;

FIG. 6 is a first side view thereof; and,

FIG. 7 is a second side view thereof.

The broken lines in the figures are included for the purpose of illustrating portions of the card with blended magnetic stripe that form no part of the claimed design.
